UNITED STATES PATENT OFFICE

LAWRENCE W. HANCE, OF PHILADELPHIA, PENNSYLVANIA

LOCOMOTIVE CYLINDER STRUCTURE

Application filed September 14, 1928. Serial No. 306,042.

My invention relates to certain improvements in compound locomotive cylinder structures of the three-cylinder type, in which the high pressure cylinder is at the centre and the low pressure cylinders are at each side of the centre beyond the frame of the locomotive.

One object of the invention is to so design the structure that the mixing chamber will extend over the central cylinder.

Another object of the invention is to so design the structure that the space under the central cylinder will be free of obstructions.

A further object is to make the walls of the passages leading from the low pressure valve chests integral with the structure.

These objects are attained in the following manner, reference being had to the accompanying drawings, in which:

Fig. 1 is a transverse sectional view illustrating a locomotive cylinder saddle for a three-cylinder compound engine, made in a single casting and illustrating the features of my invention;

Fig. 2 is a plan view of the cylinder structure;

Fig. 3 is a sectional plan view on the line 3—3, Fig. 1;

Fig. 4 is a sectional view on the line 4—4, Fig. 1;

Fig. 5 is a sectional view on the line 5—5, Fig. 1;

Fig. 6 is a transverse sectional view on the line 6—6, Fig. 2;

Fig. 7 is a sectional view on the line 7—7, Fig. 2;

Fig. 8 is a sectional view on the line 8—8, Fig. 2;

Fig. 9 is a transverse sectional view illustrating a modification of the invention, in which the structure is made in two pieces, one piece containing the central high pressure cylinder and one low pressure cylinder, and the other section containing the other low pressure cylinders; and

Fig. 10 is a sectional plan view on the line 10—10, Fig. 9.

The cylinder structure shown in Fig. 1 is made in a single casting, which rests upon

the longitudinal frames 1 of the locomotive as shown by dotted lines. The cylinder 2 in the present instance, is a high pressure cylinder, and is located preferably above the tops of the main frames of the locomotive. The space under this cylinder is clear so as to allow clearance for other mechanisms.

3—3^a are the low pressure cylinders which overhang the frames extending on each side thereof, as clearly shown in Fig. 1. 4 is a steam chest for the high pressure cylinder 2. This steam chest is connected by passages 5 at each end thereof with the ends of the cylinder 2, as clearly shown in Figs. 3 and 6. 6—6^a are the steam chests of the low pressure cylinders 3—3^a, respectively, and communicate with the cylinders through passages 7.

The mixing chamber 8 extends over the central high pressure cylinder 2, as clearly shown in Fig. 1, and connects the exhaust passages of the high pressure steam chest 4 with the intake passages of the low pressure valve chests 6—6^a. By locating the mixing chamber over the central cylinder, the chamber can be of sufficient size to allow for a much larger central cylinder than is possible with the mixing chamber extending under the central cylinder. Furthermore, it allows for a considerable "truck clearance", which is essential in engines of large capacity.

9 is a saddle which is shaped to fit the boiler of the locomotive, and the smoke-box of the boiler is cut away to allow the central portion of the cylinder structure to extend into the bottom of the smoke-box. The location of the mixing chamber in the smoke-box tends to prevent chilling of the walls of the mixing chamber.

10 is a steam inlet passage leading to the steam chest 4 of the high pressure cylinder, and the walls of this passage are cast integral with the structure. The outer end of the passage is in position so that it can be readily attached to the steam supply pipe leading from the boiler.

The walls of the exhaust passages 11—11^a leading from the two valve chests 6—6^a of the low pressure cylinders are also cast integral with the structure and also act to rein-

force the saddle 9, making a very rigid substantial structure, free of all joints except the joint within the smoke-box. These exhaust passages lead to the nozzle in the ordinary manner.

5 In Figs. 1, 2 and 3 the structure is shown as a single casting, but in some instances it may be desirable to make the device in two parts as shown in Figs. 9 and 10, in which instances the parting is at one side of the central cylinder 2^a as indicated at *x*, both sections having flanges 12 which are secured together by bolts 13, the parting preferably being on the line of one of the side frames so that the main casting containing the central 10 high pressure cylinder 2^a and the low pressure cylinder 3^b rests directly on the frames 1, while the other cylinder casting 3^b is securely bolted to the other section and to the frame. In this instance the parting is through a portion of the mixing chamber as shown.

By extending the mixing chamber above the central cylinder 2, there is sufficient space between the feet 14 which rest upon the frame of the locomotive and the central cylinder. 25 There is a space between the central cylinder and the side cylinders, and also between the several valve chests and the mixing chamber. A space likewise surrounds the exhaust 30 passages, the tubular portion forming the exhaust passages, so that access may be had to all parts of the casting for inspection and repairs at all times.

I claim:—

35 1. The combination in a three-cylinder structure of the compound type, of a centrally located high pressure cylinder and side low pressure cylinders; a valve chest for each cylinder; a steam passage leading to the valve chest of the high pressure cylinder; exhaust 40 passages leading from the valve chests of the low pressure cylinders; and a mixing chamber extending over the high pressure cylinder and communicating with the valve chest 45 of said high pressure cylinder and the valve chests of the low pressure cylinders.

50 2. The combination in a cylinder structure of the compound type, of a centrally located cylinder above the frame of the locomotive; low pressure cylinders at each side of the frame of the locomotive; a valve chest for each of said cylinders; a mixing chamber extending over the centrally located cylinder; a saddle formed integral with the cylinder structure; and tubes extending from the side 55 valve chests to the saddle in which are the exhaust passages, said tubes being integral with the cylinder structure.

60 3. The combination in a cylinder structure of the compound type, of a centrally located high pressure cylinder, said structure having low pressure cylinders overhanging the frame of the locomotive; a valve chest for each of said cylinders, said valve chests communicating with the ends of the said cylinders; a

mixing chamber extending over the central cylinder and communicating with the valve chest of the central cylinder and with the valve chests of the side low pressure cylinders; and a saddle, the central portion of said structure extending above the saddle and into the smoke-box of the locomotive.

4. The combination in a cylinder structure of the compound type, of a centrally located high pressure cylinder, said structure having low pressure cylinders overhanging the frame of the locomotive; a valve chest for each of said cylinders, said valve chests communicating with the ends of the said cylinders; a mixing chamber extending over the central cylinder and communicating with the valve chest of the central cylinder and with the valve chests of the side low pressure cylinders; and a saddle, the central portion of said structure extending above the saddle and into the smoke-box of the locomotive, the underside of the cylinder structure being above the frame and of sufficient height to allow truck clearance.

5. The combination in a locomotive cylinder structure, of a central cylinder; side cylinders; a valve chest for each of said cylinders, said valve chests communicating with each end of each cylinder respectively; a mixing chamber extending over the central cylinder, the feet of the structure resting on the side frames of the locomotive; an open space between the feet and the central cylinder, said open space extending between the central cylinder and the side cylinders and between the mixing chamber and one of the side valve chests at one end and between the valve chests on the opposite side; an inlet passage for one of said cylinders; and exhaust passages for the other cylinders, the parts being so arranged that access may be had to the space between the several parts of the cylinder structure.
